[57] CLAIM

The ornamental design of a dispenser substantially, as shown and described.

DESCRIPTION

FIG. 1 is a right, front perspective view of a dispenser incorporating our design with the dispenser handle being shown in its open position;

FIG. 2 is a right, rear perspective view thereof;

FIG. 3 is a right side elevational view thereof, the left side being a mirror-image of the right side;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a view similar to FIG. 1 with the dispenser handle being shown in its closed position.
